[57] CLAIM

The ornamental design for a computer mouse, as shown and described.

DESCRIPTION

FIG. 1 is a perspective view illustrating our design; FIG. 2 is a top view of the design shown in FIG. 1; FIG. 3 is a side elevational view taken from the left side of FIG. 2, the elevational view from the opposite side of FIG. 2 being essentially a mirror image; FIG. 4 is an end elevational view taken from the bottom of FIG. 2; FIG. 5 is an end elevational view taken from the top of the design shown in FIG. 2; and, FIG. 6 is a bottom view of the design shown in FIG. 1. The broken lines are shown in the views for illustrative purposes only and form no part of the claimed design.
